UNITED STATES PATENT OFFICE

159,900

PLASTIC CUTLERY RECEPTACLE TRAY

Harry C. Gessler, Brooklyn, N. Y., assignor to Medeo Silver Co. Inc., a corporation of New York

Application November 22, 1949, Serial No. 6,198

Term of patent 14 years

(Cl. D44—29)

To all whom it may concern:

Be it known that I, Harry C. Gessler, a citizen of the United States and resident of Brooklyn, in the county of Kings and State of New York, have invented a new, original, and ornamental Design for Plastic Cutlery Receptacle Tray, of which the following is a specification, reference being had to the accompanying drawing, forming a part thereof, and of which

Fig. 1 is a top perspective view of a plastic cutlery receptacle tray, showing my new design, and

Fig. 2 is a bottom perspective view thereof.

I claim:

The ornamental design for a plastic cutlery receptacle tray, substantially as shown.

HARRY C. GESSLER.
